UNITED STATES PATENT OFFICE.

LOUIS RYZOWICZ AND JOHN J. BOLEK, OF CLEVELAND, OHIO.

INCANDESCENT LAMP.

Application filed August 6, 1920. Serial No. 401,603.

To all whom it may concern:

Be it known that we, Louis Ryzowicz and JOHN J. BOLEK, citizens of the United States, residing at Cleveland, in the county of 5 Cuyahoga and State of Ohio, have invented a certain new and useful Improvement in Incandescent Lamps, of which the following is a full, clear, and exact description, reference being had to the accompanying drawings.

This invention relates to improvements in incandescent electric lamps and has for its object the provision of means for prolonging the life of the lamp. Other objects include the provision of manually operable means adapted to cooperate with the means for prolonging the life of the lamp to minimize the possibility of displacement when in use; together with the provision of such 20 an adjustable element that is simple, compact, capable of being cheaply manufactured and durable in use.

We accomplish the above object by providing a plurality of filaments, only one of 25 which is adapted to be in operation at one time, and we provide means for selectively rendering active any desired filament.

The means for accomplishing the above and other objects will be more fully set 30 forth in the following description which relates to the drawings, and the essential characteristics set forth in the claim.

In the drawings Fig. 1 is a longitudinal section thru the center of an incandescent 35 lamp embodying the features of our invention; Fig. 2 is a top view of the lamp; Fig. 3 is an enlarged fragmentary section showing the means for retaining a movable contact arm in position; Fig. 4 is an alternate form of the mechanism shown in Fig. 3; Fig. 5 is a top view of the lamp shown in Fig. 4.

The novel features embodied in our invention are applicable to the standard incandescent lamp, and as shown in Fig. 1, 45 10 represents the bulb of such a lamp having a hollow stem 11 secured to the threaded base 12 and adapted to be inserted in a standard socket. Extending inwardly thru 50 the base 12 and from the top portion thereof are the usual leading-in wires 13 and 14, which pass thru the stem and into the interior portion of the bulb. Secured to the 55 lower end of the leading-in wires, we provide the filaments 15 and 16, each having one

end thereof secured to a common outlet wire 17, which also passes thru the stem and out at the metallic cap 18 on the base. The filaments 15 and 16 comprise standard material and our invention contemplates the use of only one filament as a lighting medium at one time, and suitable mechanism on the base is employed to selectively render active either of the filaments.

The means for rendering active either 65 filament is shown in Fig. 3 and comprises a contact arm 20, which may be constantly urged against the conductors at the base of grooves 21, or 22, by the spring 23 acting against piston 24 within the cylinder 25. 70 The base 12 is preferably provided with a recess so that the cylinder 25 is closely fitted therein. The rod 26 may be rigidly secured to the piston 24 and be secured to the arm 20 by any suitable means as, for 75 example, by riveting. The contact arm 20 being at the top of the base constitutes one terminal and may be manually rotated about the shaft 26 to engage either of the conductors in the grooves 21 and 22. The conducting grooves may provide a recess within which the contact arm fits whereby it is 80 securely held in position.

In Fig. 4 we have shown a modified form 85 for constantly urging the contact arm with- in the conductor groove. This mechanism in brief comprises the contact arm 30 rigid with an internal cylinder 31 and slidably mounted in the cylinder 32, which like the cylinder 25 in Fig. 3 is adapted to be inserted within a recess in the base 12. The shaft 33 may be rigidly secured to the cylinder 32 or be prevented from moving outwardly therefrom by the stop pin 34, and may have the piston 35 rigid therewith. The 90 spring 36 is preferably then used to constantly urge the cylinder 31, and consequently the cylinder arm 30, downwardly within the conductor grooves 21-22 attached to the leading-in wires 13 and 14.

As shown in the drawings, the lamp is set 95 for a current to pass thru the filament 16 and the current flows thru the arm 20, conductor in groove 21, leading-in wire 15, outlet wire 17 and the metallic cap 18. Should the filament 16 be broken, the lamp is removed from the socket and the contact arm 20 is rotated about the shaft 26 until it engages conductor in groove 22. When the lamp is again inserted in the socket, the 100 105 110

path of the current is then thru the arm 20, conductor in groove 22, leading-in wire 13, filament 15, outlet wire 17 and cap 18.

From the foregoing description it will be seen that we have provided a device for selectively rendering active any one of a plurality of filaments within a lamp bulb; that we have so constructed this device that it is simple, positive in operation and adapted to be readily inserted within standard lamp bases.

Having thus described our invention, we claim:

An electric lamp having a bulb and a base therefor, said base comprising a body of insulating material and a metallic ferrule embracing the insulation, there being a portion of said insulation protruding beyond one end of the ferrule and having a frusto-con-

ical formation, spaced contact members embedded within the insulation on the side of the frusto-conical portion, and a revolute contact arm having the axis thereof centrally positioned on the base, and having an inclined portion adapted to engage said contacts, said arm providing a contact button adjacent the axis of revolution thereof whereby contact may be made with a centrally disposed contact member in a lamp socket, a plurality of leading in wires passing through the base, each connected to one of the contact members, and a common return wire passing also through the base and connected to the ferrule.

In testimony whereof we hereunto affix our signatures.

LOUIS RYZOWICZ.
JOHN J. BOLEK.
